(57) **CLAIM**

The ornamental design for a stand-alone self-supporting disposable ghost shaped baking cup, as shown as described.

DESCRIPTION

FIG. 1 is a perspective view of a stand-alone self-supporting disposable ghost shaped baking cup showing our new design;

FIG. 2 is a bottom plan view thereof;

FIG. 3 is a left side elevational view thereof; the right, front and rear side elevational views being a similar image; and,

FIG. 4 is a top plan view.

1 Claim, 4 Drawing Sheets
